DIRECTIVE ANTENNA

Armid G. Kandoian, New York, N. Y., assignor to
 Federal Telephone and Radio Corporation, New
 York, N. Y., a corporation of Delaware

Application July 17, 1944, Serial No. 545,266

7 Claims. (Cl. 250—11)

1

My invention relates to radio antenna systems. In Patent No. 2,283,897, issued May 26, 1942, to Andrew Alford is disclosed an antenna system producing substantially pure horizontally plane polarized waves. This is accomplished by so dimensioning the antenna and energizing it that the vertically polarized components of a wave are substantially neutralized in every direction from the antenna.

The arrangement in the above patent provides a radiating or receiving antenna which has radiant action only for plane polarized waves forming substantially a circular radiant action pattern in the plane of polarization. In other words, the antenna is non-directive.

It has been found that it is possible to retain the principal constructional features of the antenna disclosed in the above patent, and at the same time so energize the antenna that radiation therefrom has a maximum value in a single direction. In other words, the antenna is caused to be directive.

Accordingly one of the principal objects of the present invention is to modify the type of antenna disclosed in the patent referred to and generally known as the "Alford loop" so as to produce therefrom a radiation pattern which is not circular but which is directive in a particular direction with a minimum back radiation and with a substantially uniform field strength in said particular direction.

It is a further object of the invention to provide an antenna which is particularly suited for use with a reflector of the parabolic type, whereby radiation from the antenna toward the reflector is substantially uniform, and unreflected radiation from the antenna directly outward through the opening of the reflector is reduced to a minimum.

It is a further object of the invention to provide a directional antenna for either transmission or reception, the radiation or reception pattern of which may be altered by changing the point of connection between the antenna and the transmission line.

Further objects and advantages of the invention will be apparent from the following description of a preferred form of the invention and from the drawings, in which:

Fig. 1 is a schematic illustration of an antenna system as disclosed in the prior art;

Fig. 2 is a vectorial representation, in substance, of the instantaneous currents in the arms of the antenna of Fig. 1;

Fig. 3 is a schematic illustration of an antenna

2

system in accordance with the present invention;

Fig. 4 is a vectorial representation, in substance, of the instantaneous currents in the arms of the antenna of Fig. 3;

Fig. 5 is a schematic illustration showing the antenna of Fig. 3 employed in conjunction with a reflector of the parabolic type.

For the purpose of more clearly understanding the principles of my invention, reference is first made by way of contrast, to Fig. 1, diagrammatically illustrating an antenna 1 of the type disclosed in Alford Patent No. 2,283,897. This antenna may consist of four radiators 2, 3, 4 and 5 coupled to an R. F. translator 6 over conductors 7, 8. Radiators 2, 3, 4 and 5 are shown as curved, and so arranged as to form the periphery of a substantially closed circle. The end of each radiator is bent inwardly, as shown at 9, 10, 11 and 12, so that only the central portions thereof are utilized for radiation. The R. F. translator 6 is connected to the mid-point 13 of conductors 7, 8, and the electrical length of these conductors, which is the diameter of the circle formed by radiators 2, 3, 4 and 5, may be approximately 45°, as shown.

Radiators 4 and 5 are fed directly from R. F. translator 6 over conductor 7 and radiators 2, 3 are fed over conductor 8 through the transposition shown at 14. As a consequence current flows through the radiators in the direction indicated by the arrows. Also, since the current distribution is equal in each of the four arms due to the center connection 13, and is reversed in phase in opposite arms due to the transposition 14, the vertical field component will be substantially eliminated in every direction and for every vertical angle with respect to the antenna, as more clearly explained in the aforesaid Alford patent. Furthermore, since at any instant the current in the arms is uniform, the resulting radiation pattern will be substantially circular as indicated at 15.

Fig. 2 illustrates by scalar vectors the production of the circular radiation pattern 15 by antenna 1. As an explanation of these vector diagrams, let it be assumed that two linear conductors lying side by side are energized 180° out of phase by currents of equal amplitude. Under these conditions the fields produced by the currents in the two conductors tend to cancel one another, and the resulting radiation is substantially zero.

When the two conductors are drawn apart, however, complete cancellation no longer occurs. This is due to the fact that a certain interval of

time is required for the energy radiated from one conductor to reach the other conductor, and by that time the energy which has radiated from the latter has travelled a certain distance into space. The two radiant fields are no longer 180° out of phase, but instead have a phase difference depending on the distance between the conductors. In the form of loop illustrated in Fig. 1, it has been assumed, by way of example, that the conductors are displaced apart to such an extent that the energy in the fields produced by the two conductors have a phase displacement of 45°.

Referring now to Fig. 2a the radiation from each of the arms 3 and 2 of Fig. 1 is represented by the scalar vectors R_3 and R_2 respectively. Since these arms are fed from a common point 13 equidistant from each arm, the transposition 14 causes the currents in these arms to be 180° out of phase. If these arms 3 and 2 were superposed one on the other, or in other words if the diameter of the circle formed by the arms 2, 3, 4 and 5 were of substantially zero diameter, then the radiation from arms 3 and 2 would be represented by the vectors R_3 and R_2 , these vectors being of equal length due to the equal amplitude of the currents and extending in opposite directions due to the 180° difference in phase. However, since arms 3 and 2 are separated at their mid-points by a distance equal to approximately 45 electrical degrees, the energy radiated from 2 toward 3 is delayed 45° with respect to the energy radiated from 3, considering a direction of radiation substantially radially outward from 3. This phase-retarded radiation R_2 has been shown as R_2' in Fig. 2a, phase retardation being indicated by a counter-clockwise rotation of the vector, and phase advancement by a clockwise rotation. The total effective radiation is thus the scalar vector sum of R_2' and R_3 , or R_{23}' .

In the opposite direction, the phase of the energy radiated from 3 toward 2 is retarded in phase 45° with respect to the latter, as indicated in Fig. 2c, the effective value of the total energy radiated from 2 in said opposite direction being the scalar vector sum of R_2 and R_3 , or R_{23}'' . Similarly in Figs. 2b and 2d, the total energy radiated from arms 4 and 5 is represented by the scalar vectors R_{45}' and R_{54}'' respectively. It will be noted that

$$R_{23}' = R_{32} = R_{45}' = R_{54}''$$

or that the effective value of the energy radiated from the arms of antenna 1 is substantially equal, producing the circular radiation pattern 15.

According to the present invention, the opposite arms 2 and 3, and 4 and 5, instead of being energized by currents 180° out of phase, are energized by currents the phase of which is determined by the electrical distance between the point of connection between the R. F. translator 6 and conductors 7 and 8, on one hand, and the geometrical center of the radiating periphery on the other. In Fig. 3 the R. F. translator 6 is connected to conductors 7, 8 not at the center point 13, as was the case in Fig. 1, but rather at a point 13' which as an illustrative example is shown as 15 electrical degrees removed from the center of the periphery.

The effect of this off-center connection on the radiation characteristics of antenna 1 is illustrated in the vector diagrams of Fig. 4. In Fig. 4a, for example, the vector R_3 representing the normal radiation from arm 3 corresponding to the vector R_3 of Fig. 2a is rotated 15° counter-clockwise to assume position R_3' . This is a result

of the fact that current to arm 3 from point 13' takes 15 electrical degrees longer in time to reach arm B than does current from point 13 in Fig. 1, or in other words the phase of the current is retarded 15°.

As far as arm 2 is concerned, however, the changing of the input connection from point 13 to point 13' causes the current to reach arm 2 more quickly, due to the shorter distance through 10 which it must travel. This constitutes a 15° advancement in phase of the current to arm 2 over the original current in Fig. 1. In Fig. 4a, the vector R_2' , representing the radiation from arm 2 reaching arm 3 with a delay of 45° as shown 15 in Fig. 2a, is now advanced in phase 15° (rotated clockwise) over its value as shown in Fig. 2a to assume position R_2'' derived from R_3' , and R_2'' is appreciably shorter than vector R_{23}' of Fig. 2a, indicating that the effective value of the 20 radiation in Fig. 4a is less than that in Fig. 2a.

In Fig. 4c is shown the radiation R_2'' . The radiation from arm 3 is delayed in phase 15° in addition to its original 45° delay produced in Fig. 1 by the spacing of the radiating members. 25 In other words, vector R_3 is rotated counter-clockwise to position R_3'' . The resultant of R_2'' and R_3'' , or vector R_{23}''' , indicates that the effective value of the energy radiated is now greater than that radiated in Fig. 1 and shown in Fig. 30 2c.

In Fig. 4b the resulting vector R_{45}''' is shown to be of approximately the same magnitude as R_{32}' in Fig. 4a. Similarly in Fig. 4d the vector R_{54}''' approximately equals the vector R_{23}''' in Fig. 4c.

This produces a directional radiation pattern having a shape substantially similar to that indicated at 15'. Obviously the shape of the pattern may be varied by changing the electrical 40 spacing between point 13' and the center of the periphery. Also, the pattern may be reversed in direction by connecting the R. F. translator 6 to conductors 7, 8 on the opposite side of the center point from that shown.

While the arrangement illustrated in Fig. 3 may be utilized wherever an antenna having directional characteristics is desired, it is particularly suited for use in connection with a reflector where it is advantageous to eliminate 50 radiation directly away from the surface of the reflector. As shown in Fig. 5, antenna 1 is positioned approximately at the center of a parabolic reflector 16. As a consequence of the 55 radiation characteristics of the antenna as illustrated by pattern 15', radiation from the antenna is at a maximum in a direction toward the reflector surface, and at a minimum directly away therefrom. Both the intensity and the directional characteristics of the resulting beam are 60 thus substantially improved.

While I have illustrated the radiating arms 2, 3, 4 and 5 in Fig. 3 as being curved, they may obviously have many other shapes such as the linear configuration of Fig. 5. Likewise other means may be substituted in place of the transposition 14 for reversing the phase of the currents in the opposite arms. Furthermore, by substituting a load in place of the R. F. translator 6, the antenna 1 may be used for reception 65 instead of transmission.

While I have disclosed my invention with respect to a particular antenna system, this showing is made merely by way of illustration and is 70 not to be considered as a limitation on my invention.

tion as set forth in the objects thereof and in the accompanying claims.

What is claimed is:

1. A radio antenna system including two pairs of oppositely disposed radiating members positioned with ends spaced apart so as to form a substantially closed symmetrical coplanar periphery, each of said radiating members being short with respect to the operating wavelength, the spacing between the mid-points of the radiating members of each pair being substantially equal and equivalent electrically to less than approximately one-quarter wavelength, two substantially parallel conductors transposed at one point, said conductors respectively joining the radiating members of each of said pairs, a source of energy, and means connecting said source of energy across said conductors at a point between the electrical mid-point of said conductors and the junction of adjacent ends of said conductors respectively with two of said radiating members, whereby current circulates about said periphery in the same sense at all points, and the energy supplied to one radiating member of each of said pairs will be out of phase with the energy supplied to the other member of that pair by an amount substantially equal to twice the electrical distance between mid-point of the conductor joining the members of that pair and the point at which said conductor is connected to said source.

2. A radio antenna system according to claim 1, further comprising a parabolic reflector, said radiating members being positioned substantially symmetrically about the axis of said reflector, with the two radiating members nearest to the points at which their respective conductors are connected to said source facing the surface of said reflector.

3. A radio antenna system including a plurality of pairs of oppositely-disposed radiating members positioned with ends spaced apart so as to form a substantially closed symmetrical coplanar periphery, each of said radiating members being short with respect to the operating wavelength, the spacing between the mid-points of the radiating members of each pair being substantially equal and equivalent electrically to less than approximately one-quarter wavelength, a plurality of substantially linear conductors of equal length respectively joining the two radiating members of each of said pairs, a source of energy, and means connecting said source of energy across said conductors at a point between the electrical mid-point of said conductors and the junction of adjacent ends of said conductors respectively with two of said radiating members, whereby current circulates about said periphery in the same sense at all points, and the energy supplied to one radiating member of each of said pairs will be out of phase with the energy supplied to the other member of that pair by an amount substantially equal to twice the electrical

distance between the mid-point of the conductor joining the members of that pair and the point at which said conductor is connected to said source, to thereby produce maximum radiation in a single direction.

4. A radio antenna system according to claim 3, further comprising a parabolic reflector, said radiating members being positioned substantially symmetrically about the axis of said reflector and arranged so that the maximum effective radiation of said antenna is directed toward the vertex of said parabola.

5. A radio antenna system including four linear radiating members arranged substantially in the form of a square with their ends spaced apart, the distance between opposite members being equal to approximately one-eighth wavelength, two conductors of substantially equal length respectively connecting opposite members, a source of energy, and means connecting said source of energy across said conductors at a point between the electrical mid-point of said conductors and the junction of adjacent ends of said conductors respectively with two of said radiating members, whereby current flows in said radiating members in the same sense at all points, and the current in any member will be out of phase up to a maximum of approximately 45° electrically with the current in the member opposite thereto.

6. A radio antenna system including four oppositely-disposed radiating members arranged in substantially coplanar relation with their ends spaced apart, the distance between the mid-points of opposite members being in the order of one-eighth wavelength, two conductors respectively connecting opposite members, a source of energy, and means connecting said source of energy across said conductors at a point between the electrical mid-point of said conductors and the junction of adjacent ends of said conductors respectively with two of said radiating members, whereby current flows in said radiating members in the same sense at all points, and the current in any one member will be out of phase up to a maximum of approximately 45° electrically with the current in the member opposite to said one member.

7. A radio antenna system including a plurality of pairs of oppositely-disposed radiating members arranged with their ends spaced apart so as to form a substantially closed coplanar periphery, the distance between the mid-points of opposite members being less than approximately one-quarter wavelength, a source of energy, and two conductors of unequal length respectively feeding energy from said source to the two radiating members of each pair whereby current flows in said members in the same sense at all points, and the current in any one member will be out of phase up to a maximum of approximately 90° electrically with the current in the member opposite to said one member.

ARMIG G. KANDOIAN.
